Application April 30, 1941, Serial No. 391,082

10 Claims. (Cl. 242—45)

This invention relates to regulators, and particularly to tension regulators.

In the winding of coils of insulated wire such as are used in distribution transformers and the like, the coils are usually formed of a rectangular or irregular shape on mandrels or the like having the predetermined shape of the desired coil. The wire is wound on the mandrel at the rate of several hundred feet per minute, being unwound from a standard round supply reel that is restrained by a friction brake, to produce a tightly wound coil due to the wire tension required to overcome the friction of the reel brake.

Because of the irregular shape of the mandrel and the coil being wound, and the rapid winding rate, it is found that the wire supply reel is subjected to a harmonic acceleration that causes large variations in the wire tension. For example, as the mandrel turns, and assuming that the mandrel is rectangular in shape, as the wire is wound on the flat side of the rectangle, there is a sudden increase in the wire speed as it approaches the corner of the mandrel. The force for accelerating the wire reel is supplied by the wire as it is wound on the mandrel, with the result that the wire is sometimes jammed between the turns on the reel by the excessive tension introduced, thereby causing damage to the insulation of the wire and unduly stretching the wire. This condition is also encountered in starting the winding operation, the tension introduced tending to jam the wire between the turns of wire on the supply reel.

An object of this invention is to provide in a regulator for controlling the tension of a wire extending between a winding mandrel and a supply reel for compensating for any changes in tension encountered, and to so control the compensation as to maintain the tension substantially constant.

A further object of this invention is to provide in a regulator for controlling the tension of a wire as it is wound on a mandrel from a reel for compensating for any changes in tension encountered to maintain the tension substantially constant, and to provide for so controlling the compensation as to prevent over-compensation, and to maintain the tension substantially constant even when the mandrel is at rest.

Other objects of this invention will become apparent from the following description when taken in conjunction with the accompanying drawing, in which:

Figure 1 is a diagrammatic illustration of the 55

apparatus and circuits embodying the teachings of this invention;

Fig. 2 is a perspective view of a cam employed in a part of the apparatus embodying this invention; and

Fig. 3 is a graph, the curve of which illustrates characteristics of the generator field current obtained by employing this invention.

Referring to the drawing, and particularly 10 Fig. 1 thereof, this invention is illustrated by reference to the winding of a wire 10 on an irregularly-shaped mandrel 12 from a supply reel 14. The mandrel 12 illustrated is of rectangular shape such as is employed in industry for the 15 winding of coils for distribution transformers or the like, and is disposed to be driven at a predetermined speed by any suitable motor 16. The motor 16 comprises an armature winding 18 and a field winding 20 which are connected to any 20 suitable source of supply (not shown).

As illustrated, a motor 22 is provided for co-operating in controlling the speed of the supply reel 14 and the tension of the wire 10 between the reel 14 and the mandrel 12. The motor 22 25 comprises an armature winding 24 and a field winding 26, the field winding being separately excited from any suitable source of power (not shown). The supply reel 14 is carried on the armature shaft 28 and is, therefore, responsive to the speed of the motor 22.

A generator 30, comprising the armature winding 32 and the field winding 34, is disposed for controlling the speed of the motor 22. As 35 illustrated, the armature winding 32 of the generator 30 is directly connected across the armature winding 24 of the motor 22 for impressing a voltage across the motor, depending upon the excitation of the generator 30.

As illustrated, one end of the field winding 34 40 is connected through a resistor 36 and a variable resistor 38 to one side of the source of supply (not shown), the other end of the field winding 34 being connected through the resistor 40 to the other side of the source of supply (not shown). 45 An iron core reactor 42 is also connected across the field winding 34 of the generator 30 for co-operating to control the exciting current therein, as will be explained more fully hereinafter.

In order to further control the exciting current 50 in the field winding 34 of the generator 30, provision is made for bucking and reversing the exciting current in the field winding 34 under predetermined conditions. This is effected by impressing a direct-current voltage across the resistor 40, the impressed voltage being of a po-

larity opposite to the polarity of the voltage of the normal source of supply of the exciting current (not shown). The voltage impressed across the resistor 40 is supplied in the present embodiment from any suitable source of alternating-current supply (not shown) through the transformer 44 and the rectifying device 46, as illustrated.

In the particular embodiment illustrated, the variable resistor 38 is formed of a plurality of resistor sections which are graduated in values of resistance increasing from one end of the resistor toward the other. The graduated resistor 38 illustrated and described gives the regulator of this invention predetermined characteristics, as will be explained more fully hereinafter.

In order to control the number and sequence of resistor sections of the resistor 38, which are to be connected in series circuit relation with the generator field winding 34, a primary control device 48 is provided and disposed to be operated in a predetermined manner. The primary control device 48 is formed of a plurality of elongated conducting leaf spring members 50 having one end of each member secured in fixed spaced relation to each other and extending through suitable insulating means, such as the block 52, so that their free ends are self-biased against a sloped stop 54 of insulating material. The contact members 56 carried on the free ends will be in spaced relation to each other when the free ends seat against the sloped stop 54. Each of the fixed ends of the stack of elongated conducting members 50 is so connected by a conductor 58 to a different tap of the resistor 38 that the conducting spring members 50 of the stack are progressively connected to progressive taps of the resistor 38. An insulated driving member 60 is disposed to be actuated under predetermined conditions to progressively actuate the spring members 50 away from the sloped stop 54 to progressively shunt the resistor sections of the graduated resistor 38, beginning with the resistor sections of small value. Any suitable means for mounting the driving member 60 may be utilized, or, as illustrated, the driving member can be carried by the free ends of the leaf springs 62 which are secured at their other ends to the insulating block 52 by any suitable means (not shown). The primary control device 48 referred to hereinbefore is disclosed and claimed in the copending application of C. R. Hanna, et al. Serial No. 203,876, filed April 23, 1938, and assigned to the assignee of this invention.

The driving member 60 of the primary control device 48 is disposed to be actuated in accordance with the tension of the wire 10 between the supply reel 14 and the winding mandrel 12. As illustrated, the wire 10 is supplied to the mandrel 12 over an idler pulley 64, which is carried in a substantially non-friction manner at the end of an arm 66 mounted for pivotal movement. In practice, although only one arm 66 is shown, two of the arms 66 are provided, being disposed in spaced relation, the idler pulley 64 being carried in a ball bearing mounting (not shown) on the shaft 68 disposed between the ends of the arms 66. The other ends of the arms 66 are fixedly mounted on a shaft 70 which extends between and through suitable brackets 72, only one of which is shown, the shaft 70 being disposed to be rotated therein. The bracket 72 is mounted on a base plate 74, which can be supported in any suitable manner such as on a mo-

tor housing, or otherwise (not shown), the base member 74 also carrying elongated arms 76, 78 and 80 disposed in spaced relation to each other. The arms 76 and 80 carry stop members 82 and 84, respectively, at their free ends disposed in the path of movement of the arm 66 for limiting the extent of movement thereof.

As illustrated, the movement of the arms 66 carrying the pulley 64 in a clockwise direction about their pivotal shaft 70 is restrained by a tension spring 86 carried between the free end of the elongated arm 76 and the pulley carrying arms 66. The spring 86 is positioned to give a toggle action, so that uniform tension is maintained in the wire 10 over the entire range of the pulley travel. This is evident for as the arms 66 rotate in a clockwise direction, the spring 86 stretches and the center line of the spring approaches the pivotal shaft 70 of the pulley carrying arms 66 by just the amount sufficient to keep the wire tension constant. Changes in the tension desired to be controlled in the wire 10 may be made simply by changing the spring 86 which restrains the pulley arms 66. The toggle action referred to hereinbefore is unimpaired, if the free length of the spring is kept the same in all cases. However, where it is desired to adjust the tension of any individual spring, the adjustment may be made by means of the nut 88 and the bolt 90 which secures one end of the spring 86 to the free end of the arm 76 to change the effective length of the spring 86.

A cam 92 is carried on the end of the shaft 70 for controlling the movement of the driving member 60 in accordance with a movement of the pulley carrying arms 66. As more clearly illustrated in Fig. 2, the cam 92 is in the form of a ring member, with the slope of the cam surface progressing from the small end to the large end of the cam as the cam is rotated in a clockwise direction. The ring cam 92 is carried on the end of the rotatable shaft 70 in any suitable manner, or, as illustrated, is secured by means of the bolt 94 to the end of a block 96, which is secured to the shaft 70 as by means of brazing, or otherwise (not shown). In practice, the elements of the apparatus described are so associated that the end of the driving member 60 rides on the cam surface of the cam 92, and is directly responsive to a movement of the pulley carrying arms 66.

In operation, assuming that the wire 10 has been threaded over the idler pulley 64 to the mandrel 12, and that the motor 16 is driving the mandrel at some predetermined speed, a tension is developed in the wire 10 as it is being wound. This tension causes rotation of the pulley arms 66 and their pivotal shaft 70 against the restraining force of the spring 86 to position the arms 66 at some intermediate position between the stops 82 and 84. The rotation of the pulley arm 66 rotates the cam 92 to force the driving member 60 against the elongated conducting members 50 of the primary control device 48 to control the number of resistor sections of the resistor 38 in circuit with the exciting field 34 of the generator 30 to control the voltage impressed across the motor 22, and thereby control the speed of the reel 14.

As the mandrel 12 is driven to wind the wire 10 thereon, its irregular shape tries to change the tension of the wire 10. At the same time, because the wire is being removed from the supply reel 14, the diameter of the supply of wire on the supply reel 14 is constantly changing, so

that the speed of the reel 14 is constantly changing as the wire is unwound therefrom regardless of the shape of the mandrel 12.

Forgetting for the time being the effect of the irregular shape of the mandrel 12 upon the tension of the wire 10, and assuming that the winding of the mandrel has just started, the pulley arm 66 will be in a position adjacent the stop 82, so that substantially all of the resistor sections of the graduated resistor 38 are in circuit with the field winding 34 of the generator 30, and the exciting current therein is at a minimum for impressing a very low voltage across the motor 22 to drive the reel 14 at a very slow speed.

As the wire is unwound from the reel 14, more tension is developed in the wire 10 to effect a rotation of the pulley arms 66 in a clockwise direction about their pivot 70, and progressively drive the contact members 56 into circuit closing position to progressively shunt the resistor sections of the graduated resistor 38 from series circuit with the field winding 34. The progressive shunting of the resistor sections of the graduated resistor 38 effectively increases the excitation of the generator 30 to increase the speed of the motor 22, and consequently increases the speed of the reel 14 to maintain a constant tension on the wire 10 as the diameter of the supply of wire on the reel 14 diminishes.

With the wire 10 threaded over the pulley 64 between the supply reel 14 and the mandrel 12, and before actual winding of the wire on the mandrel 12 is started, or while the mandrel is at rest, a negative torque is developed in the motor 22 to maintain the tension in the wire 10 substantially constant. This negative torque is developed by impressing a polarity across the resistor 40 which is opposite to the polarity of the voltage of the normal exciting current supplied to the field winding 34 of the generator 30. The effect of the opposite polarity supplied through the transformer 44 and the rectifying device 46 is to buck the exciting current in the field winding 34 and provide a negative generator field current.

The cooperative effect of the bucking of the exciting current, and the variation of the resistor sections of the graduated resistor 38 through a change in position of the pulley arm 66 is illustrated in Fig. 3 of the drawing, in which the curve 98 represents the generator field current developed, starting with a full reel at rest and progressing until the reel is empty. As illustrated, because of the bucking of the normal exciting current, a negative field current is actually developed to knock down the generator residual and insure a zero speed of the motor 22, as well as develop a negative motor torque for maintaining the tension of the wire 10 at a desired value, even at zero winding speed. As the resistor sections of the graduated resistor 38 are progressively varied, beginning with the sections of small value, it is seen that the exciting current increases progressively in accordance with the amount of resistance shunted from series circuit with the field winding by the action of the driving member 60 in response to a movement of the pulley arms 66 in a clockwise direction. The graduated resistor thus compensates for the varying regulator sensitivity as the diameter of the supply of wire on the reel becomes smaller.

At the same time that the resistor sections of the graduated resistor 38 are varied, it is seen that the iron core reactor 42 cooperates with the

resistor 38 for influencing the exciting current in the field winding 34 of the generator 30, and consequently affects the speed developed in the motor 22. If the change in the resistor sections 5 of the graduated resistor 38 is a large change, shunting out large sections of the resistor 38, it is found that the impedance of the iron core reactor 42 is so great as to cause more of the current from the source of supply to immediately 10 flow in the generator field winding 34, giving an approximate rate of change correction for a change in the position of the pulley arm 66. If, however, the change in the resistor sections of the graduated resistor 38 is to cut in large sections of the resistor 38, the iron core reactor 42 functions to effect a discharge through the field winding 34 to boost the normal exciting current and prevent a quick decay in the exciting current. The iron core reactor 42 thus functions to 20 stabilize the system of this invention, giving a generator excitation proportional to the rate of change of the idler pulley arm position and compensating for system delays.

As the wire 10 is wound on the mandrel 12, the tension of the wire 10, of course, varies depending upon the position of the mandrel 12 as it is rotated by the motor 16. For example, as the wire is wound on the flat side of the rectangular-shaped mandrel 12, there is a sudden increase in the wire speed as the mandrel is rotated and the wire approaches the corner of the rectangle. The increase in the wire speed effects an increase in the tension of the wire being unwound from the reel 14, so that to prevent damage to the turns of the wire on the reel 14, or the turns of the wire being wound upon the mandrel 12, it is necessary to increase the speed of the motor 22 to increase the speed of the supply reel 14 to decrease the tension of the wire.

The increase in the tension of the wire 10 effects a rotation of the pulley arm 66 in a clockwise direction about its pivot 70 to operate the driving member 60 to shunt more of the resistor sections of the graduated resistor 38 from series 45 with the field winding 34 of the generator 30, and if the increase in tension to be compensated is a large increase, large sections of the resistor 38 will be immediately shunted from the circuit. The shunting of the resistor sections 38 causes a larger current to flow in the field winding 34, and if the sections shunted are of large value, the reactor 42 cooperates, as explained hereinbefore, to permit most of the current to flow through the field winding 34 for effecting an immediate increase in the excitation of the generator 30. This immediate increase in the excitation of the generator 30 effects an increase in the voltage impressed across the motor 22 to immediately increase the speed of the motor 22, and consequently increase the speed of the reel 14 to compensate for the increase in the tension of the wire 10 as it passes the corner of the rectangular mandrel 12.

Of course, the tension of the wire 10 is immediately decreased as the mandrel 12 is rotated to wind the wire 10 on its flat side, so that the reel 14 tends to run faster than is necessary for maintaining the desired tension in the wire 10. The decrease in the tension of the wire 10 permits the spring 86 to actuate the pulley arms 66 in a counter-clockwise direction about their pivot 70 to so move the cam 92 as to permit the spring members 62 to bias the driving member 60 away from the elongated conductor members

50 to cut in progressively smaller sections of the graduated resistor 38 in circuit with the field winding 34. The cutting in of the resistor sections of the graduated resistor 38 decreases the exciting current in the field winding 34, but if the resistor sections cut in are of such large value as would normally tend to immediately effect a large decrease in the exciting current, the iron core reactor 42 functions to prevent such immediate large decreases in the exciting current as it discharges through the generator field winding 34 to give a substantially gradual decrease or decay in the exciting current. The decrease in the exciting current in the field winding 34 effects a decrease in the voltage impressed across the generator 22, and effectively decreases the speed of the supply reel 14 to maintain the tension substantially constant on the wire 10 as it is being wound on the mandrel 12.

With the regulator of this invention, it is evident that it is possible to compensate for variations in the amount of wire on the supply reel and variations in the tension developed in the wire as it is being wound on a mandrel of irregular shape, as well as maintaining the tension substantially constant even when the mandrel is at rest. The change in the speed of the reel motor is effected immediately upon a change in the tension of the wire between the supply reel and the winding mandrel. Further, provision is made for obtaining a rate of change of correction in the speed of the motor depending upon the rate of change of the idler pulley arm position, thus compensating for system delays. The regulating action is quick and accurate, and because of the construction of the pulley arm assembly, which is usually a light, stiff frame of aluminum or other suitable light-weight metal or alloy, can follow the changes in velocity of the reel due to the irregular shape of the mandrel on which the wire is being wound with a minimum of tension disturbance due to low inertia forces.

We claim as our invention:

1. Apparatus for controlling the tension of a wire extending between a winding mandrel and a supply reel comprising, in combination, means for driving the mandrel to wind the wire thereon, a motor cooperative to control the speed of the reel and the tension of the wire, a pivotally mounted idler pulley associated with the wire and disposed for movement about its pivot as the wire tension changes, an over-center spring so associated with the pivotally mounted idler pulley as to restrain movement of the pulley about its pivot as the tension of the wire between the mandrel and the reel increases, and means comprising a variable graduated resistor responsive to a movement of the idler pulley about its pivot for controlling the speed of the motor to control the speed of the reel and the tension of the wire.

2. Apparatus for controlling the tension of a wire extending between a winding mandrel and a supply reel comprising, in combination, means for driving the mandrel to wind the wire thereon, a motor cooperative to control the speed of the reel and the tension of the wire, a pivotally mounted idler pulley associated with the wire and disposed for movement about its pivot as the wire tension changes, an over-center spring so associated with the pivotally mounted idler pulley as to restrain movement of the pulley about its pivot as the tension of the wire between the mandrel and the reel increases, and means including a variable graduated resistor

and a reactor cooperative therewith responsive to a movement of the idler pulley about its pivot and to the rate of change of the motion of the pulley about its pivot to control the speed of the motor to control the speed of the reel and the tension of the wire.

3. In a regulator for controlling the tension of a wire as it is wound on a mandrel from a reel, in combination, means for driving the mandrel to wind the wire thereon, a motor cooperative to control the speed of the reel and the tension of the wire, a generator having a field winding connected to impress a voltage across the motor to develop a torque, a variable resistor

15 having a plurality of resistor sections disposed to be connected in circuit relation with the generator field winding to control the excitation of the generator, means responsive to changes in the tension of the wire for progressively varying the number of resistor sections connected in circuit with the generator field winding to control the energization of the field winding and thereby control the torque of the motor to maintain substantially constant tension on the wire as it is being wound, and means connected in circuit relation with the generator field winding to buck the exciting current, thereby so controlling the torque of the motor as to maintain the tension of the wire substantially constant when the mandrel is at rest.

20 4. In a regulator for controlling the tension of a wire as it is wound on a mandrel from a reel, in combination, means for driving the mandrel to wind the wire thereon, a motor cooperative to control the speed of the reel and the tension of the wire, a generator having a field winding connected to impress a voltage across the motor to develop a torque, a variable resistor

25 having a plurality of resistor sections disposed to be connected in circuit relation with the generator field winding to control the excitation of the generator, means responsive to changes in the tension of the wire for progressively varying the number of resistor sections connected in circuit with the generator field winding to control the energization of the field winding and thereby control the torque of the motor to maintain substantially constant tension on the wire as it is being wound, and means connected in circuit relation with the generator field winding to buck the exciting current, thereby so controlling the torque of the motor as to maintain the tension of the wire substantially constant when the mandrel is at rest.

30 4. In a regulator for controlling the tension of a wire as it is wound on a mandrel from a reel, in combination, means for driving the mandrel to wind the wire thereon, a motor cooperative to control the speed of the reel and the tension of the wire, a generator having a field winding connected to impress a voltage across the motor to develop a torque, a variable resistor

35 having a plurality of resistor sections disposed to be connected in circuit relation with the generator field winding to control the excitation of the generator, means responsive to changes in the tension of the wire for progressively varying the number of resistor sections connected in circuit with the generator field winding to control the energization of the field winding and thereby control the torque of the motor to maintain substantially constant tension on the wire as it is being wound, and means connected in circuit relation with the generator field winding to buck the exciting current, thereby so controlling the torque of the motor as to maintain the tension of the wire substantially constant when the mandrel is at rest.

40 4. In a regulator for controlling the tension of a wire as it is wound on a mandrel from a reel, in combination, means for driving the mandrel to wind the wire thereon, a motor cooperative to control the speed of the reel and the tension of the wire, a generator having a field winding connected to impress a voltage across the motor to develop a torque, a variable resistor

45 having a plurality of resistor sections disposed to be connected in circuit relation with the generator field winding to control the excitation of the generator, means responsive to changes in the tension of the wire for progressively varying the number of resistor sections connected in circuit with the generator field winding to control the energization of the field winding and thereby control the torque of the motor to maintain substantially constant tension on the wire as it is being wound, and means connected in circuit relation with the generator field winding to buck the exciting current, thereby so controlling the torque of the motor as to maintain the tension of the wire substantially constant when the mandrel is at rest.

50 5. In a regulator for controlling the tension of a wire as it is wound on a mandrel from a reel, in combination, means for driving the mandrel to wind the wire thereon, a motor cooperative to control the speed of the reel and the tension of the wire, a generator having a field winding connected to impress a voltage across the motor to develop a torque, a variable resistor

55 having a plurality of resistor sections disposed to be connected in circuit relation with the generator field winding to control the excitation of the generator, means responsive to changes in the tension of the wire for progressively varying the number of resistor sections connected in circuit with the generator field winding to control the energization of the field winding and thereby control the torque of the motor to maintain substantially constant tension on the wire as it is being wound, and means connected in circuit relation with the generator field winding to buck the exciting current, thereby so controlling the torque of the motor as to maintain the tension of the wire substantially constant when the mandrel is at rest.

60 5. In a regulator for controlling the tension of a wire as it is wound on a mandrel from a reel, in combination, means for driving the mandrel to wind the wire thereon, a motor cooperative to control the speed of the reel and the tension of the wire, a generator having a field winding connected to impress a voltage across the motor to develop a torque, a variable resistor

65 having a plurality of resistor sections disposed to be connected in circuit relation with the generator field winding to control the excitation of the generator, means responsive to changes in the tension of the wire for progressively varying the number of resistor sections connected in circuit with the generator field winding to control the energization of the field winding and thereby control the torque of the motor to maintain substantially constant tension on the wire as it is being wound, and means connected in circuit relation with the generator field winding to buck the exciting current, thereby so controlling the torque of the motor as to maintain the tension of the wire substantially constant when the mandrel is at rest.

70 6. In a regulator for controlling the tension of a wire as it is wound on a mandrel from a reel, in combination, means for driving the mandrel to wind the wire thereon, a motor cooperative to control the speed of the reel and the tension of the wire, a generator having a field winding connected to impress a voltage across the motor to develop a torque, a variable resistor

75 having a plurality of resistor sections disposed to be connected in circuit relation with the generator field winding to control the excitation of the generator, means responsive to changes in the tension of the wire for progressively varying the number of resistor sections connected in circuit with the generator field winding to control the energization of the field winding and thereby control the torque of the motor to maintain substantially constant tension on the wire as it is being wound, and means connected in circuit relation with the generator field winding to buck the exciting current, thereby so controlling the torque of the motor as to maintain the tension of the wire substantially constant when the mandrel is at rest.

sion on the wire as it is being wound, the varying means progressively connecting smaller sections of the resistor in circuit with the generator field winding as the wire is removed from the reel to maintain a sensitive control of the excitation of the generator field winding as the reel is unwound, and means connected in circuit relation with the generator field winding to buck the exciting current, thereby so controlling the torque of the motor as to maintain the tension of the wire substantially constant when the mandrel is at rest.

6. In a regulator for controlling the tension of a wire as it is wound on a mandrel from a reel, in combination, means for driving the mandrel to wind the wire thereon, a motor cooperative to control the speed of the reel and the tension of the wire, a generator having a field winding connected to impress a voltage across the motor to develop a torque, a resistor having a plurality of resistor sections disposed to be connected in circuit relation with the generator field winding to control the excitation of the generator, the resistor being graduated with the sections progressively increasing in resistance from one end to the other, means disposed to be operated to progressively vary the number of the resistor sections connected in circuit with the field winding, means responsive to changes in the tension of the wire disposed to operate the resistor varying means to control the energization of the generator field winding and thereby control the torque of the motor to maintain substantially constant tension on the wire as it is being wound, the operation of the resistor varying means progressively connecting smaller sections of the graduated resistor in circuit with the generator field winding as the wire is removed from the reel to maintain a sensitive control of the excitation of the generator field winding as the reel is unwound, and means connected in circuit relation with the generator field winding to buck the exciting current, thereby so controlling the torque of the motor as to maintain the tension of the wire substantially constant when the mandrel is at rest.

7. In a regulator for controlling the tension of a wire as it is wound on a mandrel from a reel, in combination, means for driving the mandrel to wind the wire thereon, a motor cooperative to control the speed of the reel and the tension of the wire, a generator having a field winding connected to impress a voltage across the motor to develop a torque, a variable resistor having a plurality of resistor sections disposed to be connected in circuit relation with the generator field winding to control the excitation of the generator, means responsive to changes in the tension of the wire for progressively varying the number of resistor sections connected in circuit with the generator field winding to control the energization of the field winding and thereby control the torque of the motor, means comprising a reactor connected across the generator field winding for cooperating with the resistor as the sections connected in circuit are varied to so control the torque of the motor as to maintain substantially constant tension on the wire as it is being wound, and means connected in circuit relation with the generator field winding to buck the exciting current, thereby so controlling the torque of the motor as to maintain the tension of the wire substantially constant when the mandrel is at rest.

8. In a regulator for controlling the tension of a wire as it is wound on a mandrel from a reel,

in combination, means for driving the mandrel to wind the wire thereon, a motor cooperative to control the speed of the reel and the tension of the wire, a generator having a field winding connected to impress a voltage across the motor to develop a torque, a resistor having a plurality of resistor sections disposed to be connected in circuit relation with the generator field winding to control the excitation of the generator, means disposed to be operated to progressively vary the number of the resistor sections connected in circuit with the field winding, means responsive to changes in tension of the wire disposed to operate said resistor varying means to control the energization of the generator field winding and thereby control the torque of the motor, a reactor connected across the generator field winding, the reactor being cooperative as the resistor sections connected in circuit with the generator field winding are varied to give a sensitive control of the excitation of the generator field winding and consequently the torque of the motor to maintain a substantially constant tension on the wire as it is being wound, and means connected in circuit relation with the generator field winding to buck the exciting current, thereby so controlling the torque of the motor as to maintain a substantially constant tension on the wire when the mandrel is at rest.

9. In a regulator for controlling the tension of a wire as it is wound on a mandrel from a reel, in combination, means for driving the mandrel to wind the wire thereon, a motor cooperative to control the speed of the reel and the tension of the wire, a generator having a field winding connected to impress a voltage across the motor to develop a torque, a variable resistor having a plurality of resistor sections disposed to be connected in circuit relation with the generator field winding to control the excitation of the generator, the resistor being graduated with the sections progressively increasing in resistance from one end to the other, means responsive to changes in the tension of the wire for progressively varying the number of resistor sections connected in circuit with the generator field winding to control the energization of the field winding and thereby control the torque of the motor to maintain substantially constant tension on the wire as it is being wound, the varying means progressively connecting smaller sections of the resistor in circuit with the generator field winding as the wire is removed from the reel, a reactor connected across the generator field winding, the reactor cooperating with the resistor as the sections connected in circuit are varied to so control the excitation of the generator field winding as to maintain a sensitive control of the torque of the motor and thereby maintain a substantially constant tension on the wire as it is being wound, and means connected in circuit relation with the generator field winding to buck the exciting current, thereby so controlling the torque of the motor as to maintain the tension of the wire substantially constant when the mandrel is at rest.

10. Apparatus for controlling the tension of a wire extending between a mandrel and a supply reel comprising, in combination, means for driving the mandrel to wind the wire thereon, a motor cooperative to control the speed of the reel and the tension of the wire, a pivotally mounted idler pulley associated with the wire and disposed for movement about its pivot as the wire tension changes, an overcenter spring so asso-

ciated with the pivotally mounted idler pulley as to restrain movement of the pulley about its pivot as the tension of the wire between the mandrel and the reel increases, a plurality of self-biased contact members disposed for progressive movement to control the speed of the motor, and a cam actuated by the pivotally

5 mounted idler pulley disposed for translating the pivotal movement of the pulley about its pivot to a straight line movement to actuate the contact members progressively.
